UNITED STATES PATENT OFFICE

LOUIS E. PITTONI, OF JAMAICA, NEW YORK, ASSIGNOR TO THE ROME COMPANY, INC.,
OF ROME, NEW YORK, A CORPORATION OF NEW YORK

MATTRESS

Application filed August 25, 1930. Serial No. 477,497.

My present invention relates to the manufacture of mattresses and similar articles of the type in which a suitable filling material, such as felt, curled hair, or cotton, is held in position within a ticking or cover by tufting cords, which extend vertically through the filling material and cover at spaced points and are normally held in that position by tufts or tufting members arranged on the 5 cover, thereby preventing the ends of the cords from tearing through the cover when in use.

It has been the usual practice heretofore to connect such tufting cords, preferably in 15 loop form, to the tufts on the outer surfaces of the cover by looping the cords about the tufts. Various types of tufts have been devised for this work, but none have proved to be entirely satisfactory or given satisfaction commensurate with their cost of production and installation. Common arrangements are to loop the outer ends of the tufting cords over washers of leather or felt, bunches of fibers or balls of yarn. Such arrangements have proved unsatisfactory because such tufts frequently become disconnected and lost when the cords become slack during use and also because of the tendency of dust and dirt to gather under the tufts 25 and thereby render the cover unsightly and unsanitary.

Tufts have also been formed by metallic gromet or eyelet members, arranged to extend through openings formed in the upper 35 and lower cover members and to which the tufting cords are connected. Such arrangements are disadvantageous because the cord stresses in use must be borne by the already weakened portions of the cover immediately adjacent the tuft openings. These stresses frequently cause the openings to become enlarged and the tufts to be pulled inside the cover. In many cases, either because of the 40 particular construction or disarrangement of the tufts these members can be felt through

the bedding with consequent discomfort to the user.

The object of my present invention is the provision of an improved mattress construction which is characterized by tufting members which will remain fixed in position under substantially all conditions of use; which do not require corresponding openings in the cover members; which reinforce, and distribute the stresses thereon to, a substantial 50 portion of the cover; which enhance the appearance of the mattress; and which can be efficiently and economically applied.

The various features of novelty which characterize my invention are pointed out 55 with particularity in the claims annexed to and forming a part of this specification. For a better understanding of the invention, however, and the advantages possessed by it reference should be had to the accompanying 60 drawing and descriptive matter in which I have illustrated and described a preferred embodiment of the invention.

Of the drawing:

Fig. 1 is a plan view of a mattress incorporating my invention;

Fig. 2 is a section on the line 2—2 of Fig. 1;

Fig. 3 is a plan view of one corner of the mattress on a larger scale showing the tufting member in an incomplete form; and

Fig. 4 is a plan view of the mattress portion shown in Fig. 3 with the tufting member completed.

In the preferred embodiment of my invention illustrated in the drawing, A designates 80 a mattress provided with a cover or ticking B enclosing a suitable filling material C in a well known manner. Tufting cords D of the usual character are adapted to be inserted through the filling material C and upper and lower members of the cover B' and B², respectively, at points distributed over the mattress and to be connected to tufts or tufting members E arranged at corresponding points on 85 90

the cover members and constructed in a manner hereinafter described.

In accordance with my invention, each of the tufting members is formed by one or more strands E' of a thick thread, preferably embroidery silk, arranged on the cover as a group of stitches. These stitches are preferably parallel, closely spaced, and longer than the width of the group, as shown in Fig. 3. In this operation no contraction of the fabric 5 is effected and each stitch is preferably formed with a single loop exposed on the outer side of the fabric and with a short connecting portion to the adjacent stitch underneath.

When a sufficient number of the stitches 15 have been made, the free end of the strand, designated by E^2 , is repeatedly looped around the intermediate portions to bind them together in a substantially butterfly formation, as shown in Fig. 4. The free end of the 20 strand is then passed through the fabric and the tuft is completed. The relatively soft character of the strand material used and the arrangement of the binding portion in a flat loop forms a tuft which projects only a slight 25 distance above the surface of the cover and which cannot cause any discomfort to the user of the mattress. The embroidery strand employed is preferably of a color harmonizing 30 with the color or design of the mattress cover and enhances rather than detracts from the appearance of the fabric, particularly when the resulting configuration is of a more or less ornamental nature.

In commercial practice, the tufts can be 35 applied by passing a fabric strip from a roll of the desired width through gang sewing machines of a type suitable for such work to simultaneously form a number of tufts at 40 an extremely low cost of manufacture.

With the cover members B' and B^2 arranged with corresponding tufts in vertical alignment and the filling material in position, the tufting cords D , respectively in loop form 45 are passed through the mattress and over the bunched portions of each pair of tufts. The free ends of the cord are then connected in the usual manner. Similar operations are performed for each pair of tuft members until the tufting operation is completed.

The arrangement of the end portions of the tufting cords in parallel with the looped 55 portions of the strand free end is advantageous as the cord works itself down between adjacent looped portions and is substantially concealed therein. By the present tuft construction, the stresses on the tufts, exerted by the tufting cords, are transmitted to a substantial portion of the cover member area surrounding the points where the tufting cords 60 pass through the fabric. The described connection of the tufts with the fabric avoids any possibility of the tufts being worked loose in use or of the fabric being torn at this 65 point.

While in accordance with the provisions of the statutes, I have illustrated and described the best form of embodiment of my invention now known to me, it will be apparent to those skilled in the art that changes may be made in the form of the device disclosed without departing from the spirit of my invention as set forth in the appended claims and that in some cases certain features of my invention may be used to advantage without a 70 corresponding use of other features.

Having now described my invention what I claim as new and desire to secure by Letters Patent, is:

1. A mattress having upper and lower cover members, a filling material arranged therebetween, and tufting means for holding said filling material in position and comprising a strand of material arranged to form a group of adjacent reinforcing stitches at a predetermined point on the outer side of one of said cover members, and a tufting cord extending through said filling material and cover members and looped about said 80 stitches.

2. A mattress having upper and lower cover members, a filling material arranged therebetween, and tufting means for holding said filling material in position and comprising a strand of material arranged to form a group of relatively long and parallel reinforcing stitches at a predetermined point on the outer side of one of said cover members, and a tufting cord extending through said filling material and cover members and looped about an intermediate portion of said 85 stitches.

3. A mattress having upper and lower fabric cover members, a filling material arranged therebetween, and tufting means for holding said filling material in position and comprising a strand of material arranged to form a group of reinforcing stitches adjacent one another at a predetermined point on the outer side of one of said cover members, the free end of said strand being wrapped around said stitches in a flat loop at said predetermined point, and a tufting cord extending through said filling material and cover members and looped about the 90 bunched portion of said stitches.

4. A mattress having upper and lower fabric cover members, a filling material arranged therebetween, and tufting means for holding said filling material in position comprising a group of relatively long stitches on one of said cover members, means for bunching said stitches together at a point intermediate their length, and a tufting cord extending through said filling material and cover members and looped about said stitches at 95 said intermediate point.

5. A mattress having upper and lower fabric cover members, a filling material arranged therebetween, and tufting means for 100

holding said filling material in position and comprising a group of relatively long stitches secured to and reinforcing a predetermined area of one of said cover members, said stitches being interconnected in a butterfly formation, and a tufting cord extending through said filling material and cover members and looped about an intermediate portion of said reinforcing stitches.

Signed at Long Island City, in the county
10 of Queens and State of New York, this 21st
day of August, A. D. 1930.
